UNITED STATES PATENT OFFICE.

JAMES ROBERTS HUGHES, OF BELLEFONTE, PENNSYLVANIA.

EDUCATIONAL GAME.

SPECIFICATION forming part of Letters Patent No. 656,117, dated August 14, 1900.

Application filed March 24, 1900. Serial No. 10,025. (No model.)

To all whom it may concern:

Be it known that I, JAMES ROBERTS HUGHES, of Bellefonte, in the county of Centre and State of Pennsylvania, have invented 5 a new and useful Improvement in Educational Games, of which the following is a specification.

The object of my invention is to provide a means for teaching the conjugation of the 10 Latin verb and of impressing it upon the memory and at the same time imparting to it the attractive and interesting features of a game which will appeal even to the dull student and insure a proper knowledge of 15 this important element of the Latin language by the easy and effective method of object teaching.

My game is to be entitled "Railroading Through Latin Verbs," and it contemplates 20 a "Verb station" and four gates leading to as many tracks, each gate and its corresponding track being named to represent one of the principal parts of the Latin verb—*i. e.*, the present indicative, the present infinitive, 25 the perfect indicative, and supine. At suitable intervals along each track are arranged small stations representing the several tenses derived from the principal parts of the verb marking that gate and track, the active voice 30 being placed on one side of the track and the passive voice on the other. Suitable movable figures, constructed as little images representing passengers, are arranged within the station-floor in miscellaneous relation, and 35 each image is marked with a name of a different tense of the verb. The game is to be played by spinning an indicator, which, stopping at the name of a certain tense, calls for the student to take up that image, place him 40 on his proper car on the track representing the principal part of the verb from which he is derived, and run him down to his individual station.

A railroad-guide indicating in juxtaposition the form of the verb, the name of its tense, (or station,) and the gate and track to which it belongs is provided, all as will be hereinafter fully described.

Figure 1 is a perspective view of the station 45 and tracks delineated on two pieces of cardboard set up in proper relation and representing also the dummy passengers in the stations. Fig. 2 is an enlarged view of one

of the gates and tracks representing the present indicative mood and the active and passive tenses derived therefrom. Fig. 3 is the railroad-guide; Fig. 4, the spinning indicator, which calls for the order of play; and Fig. 5 is a detail of one of the passenger-images.

One large piece of cardboard A serves as a 60 foundation, at the top of which is built or erected of some stiff material a detachable main station B, in which the men or passengers are in waiting. On the tower is painted a clock C, "Verb station," and under these 65 the Latin verb "Amo" or any other. Below the station on the flat cardboard A are painted four tracks running in different directions. At the head of these tracks four gates are painted. To one side of each gate is painted 70 a pennant bearing the number of the gate, the principal part of the verb naming the gate, and the corresponding Latin form.

Small stations deriving their names from the tenses formed from the part on the pennant at the head of the track are painted on either side at proper distances, the active on one side and the passive on the other, and in the order in which they occur in the conjugation. Sign-boards are painted on the stations with the names of the stations thereon indicated by tenses.

A guide D is provided containing in alphabetical order all the Latin forms of the verb, with the name of the form set opposite to it 85 and the number of the track to which it belongs. The player when in doubt as to where a form belongs can consult the guide and locate it readily.

A little image E represents each form (or 90 passenger) bearing the name of that form of the verb and the number of the track on which it is located, as seen in Fig. 5. This is constructed in a simple way with a base of a character to enable it to stand easily.

A toy engine F, called "Traho," drawing 95 a coach with the letters "L. R. R." ("Latin Rail Road") painted on it, is provided to run at the will of the player in conveying the men to their respective stations. These may 100 be dispensed with when older students are playing. When the passenger is known, he can be placed directly with the hand in his proper station. The toy feature is for the use of children. An indicator G contains all 105 the tense forms of the active and passive

voices arranged in circular order and bears a central index-hand or pointer which may be spun around and which when stopping at any particular verb form indicates that that 5 passenger is to be sent to his destination.

Directions for playing: Lay down the foundation-piece A, containing the gates and tracks, according to the position given in Fig.

1. At the head of this build up or erect the 10 main station B, opening upon the gates and tracks. Set up the passengers E in the space between the main station and the gates. Place the "Railroad-guide" in a conspicuous place. Place the train on track No. 1.

15 Now spin the pointer of the "Indicator." It will point to a Latin form. Hunt it up among the forms (passengers) in the waiting-rooms.

If you are in doubt as to what gate he must 20 pass through and what station he is destined for, immediately consult the "Guide," and it will tell you all. Put the man in the car and run him to his station and place him thereon. If you want to spin twice in succession or even oftener to see if more than one pas-

25 senger in succession is to be conveyed to stations on the same track, so as to make better time in accomplishing your purpose, it is permissible.

Older players, as already intimated, need 30 not use the toy feature of engine and car. They may simply find the passengers and place them at the proper stations. At the beginning of the game the car and engine stand at the head of track No. 1. Every time 35 the passenger is conveyed to his station the car must be pushed back to the head of that track before spinning the indicator again. If the pointer stops at a form already designated, take the form named next on the right.

40 Note the time when the player begins and when he finishes, locating all the thirty-three (33) passengers, and this record of time is made and preserved.

Only one at a time can play in the actual 45 operation of the game, the object being to ascertain how long it requires the player to convey the several men to their proper stations or in reality to locate the various forms of the verb, and thus test his or her knowledge of 50 the same; but while one is playing others, young or older, will be interested in watching and by watching will be learning.

One player after another locates the passengers, and that one is the winner who has 55 made the "best time." In other words, the victor will be he who has the best knowledge of the passengers and stations. After perfect familiarity with the parts of the verb has been acquired then a substitution can be made in 60 the mind and the game played with any other verb of the different conjugations as a model.

This game can be played in any country, the only change needed being that of the 65 translation of the directions into the language of that country.

The power of association is so strong that the child mind can readily learn in an amus-

ing way the tenses of a Latin verb and their corresponding forms, and when they begin the study of the Latin verb at school the 70 harder task will have been accomplished, nothing remaining but the easier part—the inflections.

Latin will always be studied as a classic, and as the verb is the leading word of every 75 Latin sentence its easy conjugation and means for memorizing the same is a matter of great importance.

Having thus described my invention, what I claim as new, and desire to secure by Letters 80 Patent, is—

1. An educational game comprising a representation of a main railroad-station, a series of tracks representing the principal parts of the verb and having stations along the said 85 track representing the tenses derived from said principal parts of the verb, and movable images representing passengers and bearing the various names of the forms of the verbs and adapted to be transferred to their proper 90 stations substantially as described.

2. An educational game comprising a representation of a main railroad-station, a series of tracks representing the principal parts 95 of the verb and having stations along the said tracks representing the tenses derived from said principal parts of the verb, movable images representing passengers and bearing the various names of the forms of the verb, and a railroad-guide bearing the names of the 100 forms, the tenses, and the tracks or gates to which they belong substantially as described.

3. An educational game comprising a representation of a main railroad-station, a series of tracks representing the principal parts 105 of the verb and having stations along the said tracks representing the tenses derived from said principal parts, movable images representing passengers and bearing the various names of the forms of the verb, and a spinning indicator having the forms of the verb 110 displayed in circular series, and a central revolving index-hand or pointer substantially as described.

4. An educational game comprising a representation of a main railway-station, a series 115 of tracks representing the principal parts of the verb and having stations along the said tracks representing the tenses derived from said principal parts of the verb, one or more 120 dummy trains arranged upon said tracks, and movable images representing passengers and bearing the various names of the forms of the verb adapted to be transferred to the trains 125 and run to their respective stations substantially as described and for the purpose set forth.

In testimony whereof I have signed my name to this specification in the presence of two subscribing witnesses.

JAMES ROBERTS HUGHES.
